(57) **CLAIM**

The ornamental design for a chicken saddle, as shown and described.

DESCRIPTION

FIG. 1 is a top perspective view of a chicken saddle, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

FIG. 9 is another perspective view thereof, but shown in a usage state in an environmental view.

FIG. 10 is another perspective view thereof, but shown in a usage state in an environmental view; and,

FIG. 11 is an enlarged detail view of area 11 in FIG. 1. The broken lines depicting a chicken shown in FIGS. 9 and 10 illustrate environmental structure. The other dash-dot broken lines illustrate portions of the chicken saddle. The dash-dot-dot broken lines represent the boundaries and indicator of the enlarged view. The broken lines form no part of the claimed design.
